UNITED STATES PATENT OFFICE.

SOLOMON LINDENBERGER, OF TOLEDO, OHIO.

OAR.

SPECIFICATION forming part of Letters Patent No. 298,485, dated May 13, 1884.

Application filed October 22, 1883. (No model.)

To all whom it may concern:

Be it known that I, SOLOMON LINDENBERGER, a citizen of the United States, residing at Toledo, in the county of Lucas and State of Ohio, have invented certain new and useful 5 Improvements in Boat-Oars, of which the following is a specification.

My invention relates to certain improvements in boat-oars; and it consists in an improved method of coppering the paddle end of the oar, and in using, in connection with the rowlock, a removable flexible or partially flexible ring for holding the oar in proper position, and for preventing its falling into the 15 water should the operator release his hold upon the handle. I attain my object by mechanism illustrated in the accompanying drawings, in which—

Figure 1 is a view of the entire oar, showing 20 the edge of the paddle, and at its lower end is shown the coppered part above mentioned, and near the upper extremity is shown the removable flexible ring. Fig. 2 is also a view of the entire oar, showing the flat side of the 25 paddle, and near its upper end is also shown the removable flexible ring and a rowlock of modern construction. Fig. 3 is a view in perspective taken between the lines *a* and *b*, Figs. 1 and 2, showing the rowlock and the removable flexible ring separated from each other. Fig. 4 is an enlarged plan of the copper covering as it appears when cut into the proper 30 form and after the rivet-holes have been punched and otherwise completed ready to bend about the lower extremity of the paddle end of the oar, as shown in Fig. 5. Fig. 5 is also an enlarged plan of the extremity of the 35 paddle as it appears when coppered and riveted and otherwise completed ready for use. Fig. 40 6 is an edge view of Fig. 5 taken on line *d*, showing the appearance of the ears *D* and of the edge joint made by the folding of the copper about the end of the paddle, and also showing the method of fastening the said copper by riveting through the several folds of the 45 wrap and the wood and heading the ends of the rivets.

The shaft or handle *E* is commonly made either round or oval and of a curved or tapering form, and generally partly covered with leather, as shown at *G*. The paddle end *H* is made in various forms and often curved, as

shown at *H'*. The lower extremity of the paddle is covered with copper to prevent abrasion and wear, and it is desirable to have this part 55 light in weight and as strongly secured to the wood as the nature of the material will admit. The old method of accomplishing this object was very faulty and inadequate. It consisted in doubling the sheet, closing the ends upon 60 the edge of the paddle, nailing the said copper to the wood by punching through one side, driving the nail through the perforation and through the wood against the copper upon the opposite side, which caused the end striking 65 the copper to double up or clinch.

My improvement consists, first, in riveting the said copper to the oar by passing a rivet through the several folds of the wrap and heading its ends upon the wrap, as shown at 70 *K*, Figs. 2, 5, and 6; also, in the novel form of the copper wrap having the ears *D*, which are preferably made to fold upon opposite sides, as shown in Fig. 5; but the sheet may be cut in such a form as that the ears *D* may all fold 75 upon one side without changing the nature of my invention.

The second part of my invention relates to the removable flexible ring *I*, which becomes necessary in consequence of the change in the 80 form of the rowlock *J*, which is now preferably made in a circular or ring form, as shown at *J'*, Fig. 3, instead of being bifurcated in the old and well-known manner. The old and well-known style of ring which my flexible 85 ring supersedes was commonly made up of strips of leather wound about the shaft and nailed, and, in combination with the bifurcated rowlock, it gave no inconvenience; but when the ring or circular rowlock came into use, as 90 it was necessary to place the said rowlock between the paddle and the ring, the ring must first be removed in order that the handle or shaft might pass through the ring-rowlock, after which the leather ring was again nailed 95 to the shaft, as before. It is apparent that my removable flexible ring obviates this difficulty, and by its use a set of rowlocks can be readily applied to the oars and detached at pleasure, since the tension of the flexible ring is sufficient to firmly secure it to the shaft without 100 nails or other fastening.

I am aware that prior to my invention boat-oars have been made with their paddle ends

covered with copper or other metallic plate tacked thereto. I am also aware that a non-elastic ring for holding a boat-oar in position relatively to the rowlock has been applied 5 and tacked to the oar in a well-known manner. I do not therefore claim these, broadly.

I am familiar with the patents of Mason Britton, No. 191,923, June 12, 1877, and of Michael F. Davis, No. 282,856, August 7, 1883, 10 and disclaim any invention therein contained; but

What I do claim as my invention, and desire to secure by Letters Patent, is—

As a new article of manufacture, an oar

the paddle end of which is made in nearly a 15 rectangular form, and covered with a plate of any suitable material, said plate having ears adapted to be folded over upon the sides of the oar, and forming at the point of contact of said ears and sides two thicknesses of metal 20 or material, in combination with means for uniting the whole securely together, substantially as shown, and for the purpose described.

SOLOMON LINDENBERGER.
